UNITED STATES PATENT OFFICE

2,439,539

VALVE FOR SPRAY BARS

William E. Cellwork, Kansas City, Mo., assignor to Standard Steel Works, Kansas City, Mo., a corporation of Missouri

Application December 18, 1944, Serial No. 568,610

3 Claims. (Cl. 137—21)

1

This invention relates to spray bars for distributing machines and particularly to the spray nozzles thereof through which a bituminous or like material is discharged onto a roadway, the principal objects being to provide a spray bar and nozzles of simple, inexpensive, and relatively light weight construction; to provide a structure requiring few threading and tapping operations in the production thereof; to provide a valve and nozzle assembly that is readily removed from the spray bar for inspection and repair or for replacement with a new assembly; and to provide a structure wherein the valve assemblies are readily connected and adjusted for simultaneous operation.

Other objects of the invention are to provide a valve structure having a tapered valve head, and a relatively large area retained in sealing contact with a tapered seat in the valve body by a spring located within the flow passage between the point of cutoff and the outlet of the spray nozzle so that the valve is leak-tight and in case it is necessary to apply heat for melting any of the material that solidifies within the bar or valves, the spring is heated no hotter than the material contained in the passageway.

It is also a prime object of the invention to provide a valve structure having a substantially short flow passage from the point of cutoff to the outlet of the spray nozzle, thereby reducing possibility of material congealing therein and to avoid dripping of material after the valve is closed.

In accomplishing these and other objects of the invention, I have provided improved structure, the preferred form of which is illustrated in the accompanying drawing wherein:

Fig. 1 is a perspective view of a section of a spray bar equipped with valve and nozzle assemblies embodying the features of the present invention.

Fig. 2 is an enlarged perspective view of a fragmentary section of the spray bar and showing the spray nozzle and valve assembly in position for application to the spray bar.

Fig. 3 is a cross section through the spray bar at the point of one of the valve and spray nozzle assemblies.

Fig. 4 is a cross section through the valve assembly.

Referring more in detail to the drawing:

1 designates an end of a fixed section of a spray bar such as used on a distributing machine and 2 designates the adjacent swing section that is connected to the fixed section by a hinge joint

2

3. The sections of the spray bar each include joints of tubing 4 suitably connected together to form spray bar sections of the desired length, the tubes 4 having inner tubes 5 supported therein at one side of the horizontal center thereof and which are adapted for interconnection when the tubes are connected together by the joints 6 whereby the spray bar is provided with flow passageways 7 and 8 through which a material to be distributed is circulated throughout the length of the spray bar sections and returned so as to maintain the material in the spray bar in fluid condition and effect heating of the parts thereof by the hot material under circulation. The spray bar units composing the respective sections are provided in the upper and lower sides thereof with openings 9 and 10 formed through the wall of the outer tubes as best shown in Figs. 2 and 3 for accommodating valve and spray nozzle units 11 through which the circulated material is discharged from the distributor bar in spray form when the valves of the assemblies are opened.

Each assembly includes a valve body 12 having a tapered tubular barrel portion 13 for rotatably mounting the stem of the valving member later described. The valve body also includes a flaring portion 14 at the lower end of the barrel and which has a tapering bore 15 coaxial with the bore 16 of the barrel as shown in Fig. 3. Formed exteriorly of the flared portion of the valve body at the larger end thereof is an annular flange 17 having an upper face 18 conforming to the contour of the underside of the spray bar units surrounding the openings 10. The flange 17 seats thereon a gasket washer 19 to form a seal between the flange 17 and the spray bar unit in which the valve assemblies are installed. The barrel is of sufficient length to project through the opening 9 and the projecting end 20 is externally threaded to mount a jamb or draw nut 21 thereon. Sleeved on the projecting end of the barrel under the draw nut is a washer 22 having an underface 23 conforming in contour to the upper side of the bar unit to accommodate a gasket 24 similar to the gasket 19 previously mentioned. The lower end of the flaring portion 14 of the valve body terminates in a neck 25 having a counterbore 26 cooperating with the enlarged end of the tapered bore to form an annular shoulder 27. The neck 25 is provided with external threads 28 to engage threads 29 on a union nut 30 which cooperates with the shoulder 27 to retain a spray nozzle 31 later described.

Rotatably mounted within the valve bodies are valving members 32 having heads 33 tapered in

accordance with the tapered bores of the valve bodies whereby the tapering surfaces 34 thereof are adapted to sealingly contact the surface of the tapering portions 15 to effect seals therebetween. The valving members also include stems 35 coaxial with the heads 33 and of a size to be freely rotatable within the bores 16 of the barrel portions of the valve bodies. The stems are of sufficient length to project beyond the outer ends of the threaded portions of the barrels and are suitably shaped as at 36 to mount the hubs 37 of laterally extending operating levers 38 whereby the valve stems may be oscillated within the valve bodies. The flaring portion of the valves have ports 39 extending through the walls thereof and preferably elongated in the axial direction of the valve assembly as shown in Fig. 4, through which material in the passageway 7 is adapted to flow when ports 40 in the valve heads are moved into registration therewith. The ports 40 form the inlets to L-shaped ducts 41 which open downwardly through the lower ends of the tapered heads and connect with counterbores 42 which form annular seats 43 for springs 44. The nozzles previously mentioned comprise cylindrical bodies 45 having flange-like portions 46 and cylindrical necks 47, the necks being projected through openings 48 in the union nuts so that the union nuts clamp the flanged portions of the nozzles against the annular shoulders 27 to retain the nozzles from rotation. The spray nozzle bodies have axial bores 49 through which material to be distributed is discharged through slot-like ports 50 extending transversely across the neck portions 31 as shown in Fig. 3. The nozzles 49 have counterbores 51 at their opposite ends to cooperate with the counterbores 42 for accommodating the valve seating springs 46 which retains the tapered valve heads in sealing contact with the tapering surface of the valve bodies so as to prevent leakage therebetween and assure flow of material from the ports 39 to the ports 41 when the valving members are moved to discharge material to the spray nozzles.

It will thus be noted that the springs are located within the relatively short passageway between the points of cutoff and the outlets of valve nozzles so that should it become necessary to apply heat to the bar for melting any material congealed in the bar therein, the springs can become no hotter than the material in the passageways which contain the springs. Therefore, possible injury to the springs is avoided and the springs retain their original tension necessary to maintain proper sealing contact of the tapered surface.

The arms 38 of the valves are connected by a series of links 52 whereby all the valves of the spray bar are simultaneously operated. The links 52 for each hinge section are in two parts 53 and 54 which are connected by turn buckles 56 whereby the positions of the arms 38 of the valves may be adjusted relative to each other.

The links 52 are reciprocated by a rod 57 having pivotal connections 58 at the axis of the hinge joints 3 with a rod 59 adjustably mounted in ears 60 depending from the adjacent links of the hinge sections, the rod being threaded and provided with adjusting nuts 61 and 62 engaging the respective sides of one of the ears. By adjusting the nuts, the point of cutoff relatively to the inlet ports of the valves may be regulated so that the sprays operate simultaneously.

In assembling the parts of a valve unit, the stem of the valving member is passed through the barrel so that the head thereon engages the tapered bore of the valve body. The spring is then inserted in the counterbore 42, after which the nozzle 31 is inserted into the valve body to engage the shoulder 27, the lower end of the spring being received in the counterbore 46 of the nozzle. The union nut 30 is then applied and after adjusting the direction of the slot-like port, the union nut is tightened to clamp the nozzle in adjusted position.

In assembling the valve in one of the bar sections, the gasket ring 19 is sleeved over the barrel 13 of the valve body to seat on the flange 17. The barrel of the valve body is then inserted through the large opening 10 into the tube 4 and through the small opening 8 so that the threaded end projects therefrom. The gasket 24 is then applied over the threaded end of the barrel followed by the washer 22 and draw nut 21. Upon tightening of the nut 21, the gaskets 19 and 24 are pressed against the tubing to effect a fluid-tight seal. After application of the valve units, the lever arms 38 are applied to the shaped ends 36 of the valve stems and the arms are connected by the links 52. The links of the swing sections are then connected by the turn buckle and the arms adjusted so that they all extend in the same direction. The actuating bar 57 is then connected and the nuts 60 and 61 adjusted to provide the desired degree of cutoff for the valves.

In operating the valves, shifting of the connected links swing the valve arms to move the valving members so that the ports 40 are carried from a position out of alignment with the ports 39 to a position in alignment therewith so that passageways are opened from the interior of the spray bar to the nozzles and wherethrough the liquid is discharged under pressure in spray form through the slots 50. The position of the slots 50 may be adjusted to locate the sprays for desired coverage by loosening the union nuts and turning the nozzles 31 therein after which the nuts are retightened.

From the foregoing, it is obvious that I have provided a spray bar and nozzle unit which results in a simple and inexpensive, light weight construction and which requires a minimum of threading and welding operations.

It is also obvious that I have provided a valve and nozzle assembly that is readily removed from the spray bar for inspection or repair or, when required, replacement with a new assembly.

It is also obvious that the operating levers of the valves are all readily connected and are adjustable for simultaneous operation of all the sprays.

What I claim and desire to secure by Letters Patent is:

1. In an apparatus of the character described, a substantially cylindrical tubular member through which a liquid is to be circulated and having differential sized openings in opposite walls thereof, a valve housing extending through said openings and having a tapered valve chamber with the base thereof closing the larger of said openings, said valve housing having a bore coaxial with said chamber, an annular flange on the valve housing at the base of said chamber and encircling the larger of said openings and having curvature to conform with the curvature of the tubular member to seat the flange and prevent rotation of the valve housing in said openings, a washer sleeved

on the housing and encircling the smaller of said openings, said washer also being curved to conform with the tubular member, gaskets between the washer and tubular member and between the tubular member and said flange and encircling the openings on the outer sides of said members, a nut having threaded connection with the valve housing and engaging the washer to draw said gaskets into sealing contact with the sides of the tubular member while the valve housing and washer are prevented from turning by said curved engagement with the tubular member to effect seals between the valve housing and the tubular member, a valve member having a tapered head in the tapered valve chamber and having a shank oscillatably mounted in the coaxial bore, and means having connection with the valve housing on the exterior side of said flange for retaining the valve member in the valve housing.

2. In an apparatus of the character described, a substantially cylindrical tubular member through which a liquid is to be circulated and having openings in opposite walls thereof, a valve housing extending through said openings and having an axial bore, an annular flange on the valve housing encircling one of said openings and having curvature to conform with the curvature of the tubular member to seat the flange and prevent rotation of the valve housing in said openings, a washer sleeved on the end of the housing extending through the other of said openings, said washer also being curved to conform to the tubular member, gaskets between the tubular member and washer and the tubular member and said flange to seal said openings, a nut having threaded connection with the valve housing and engaging the washer to draw said gaskets into sealing contact with the sides of the tubular member while the valve housing and washer are prevented from turning by said curved engagement with the tubular member, a valve member having a shank oscillatably extending through the axial bore and projecting from the end of the valve housing which carries the washer, an arm fixed to the stem for oscillating the valve member, and means having connection with the valve housing on the exterior side of said annular flange for retaining the valve member in the valve housing.

3. In an apparatus of the character described, a substantially cylindrical tubular member
